FLUID HEAT EXCHANGE APPARATUS

David S. Jacobus, Montclair, N. J., assignor to
The Babcock & Wilcox Company, Newark,
N. J., a corporation of New Jersey

Original application November 20, 1934, Serial
No. 753,828. Divided and this application
October 16, 1937, Serial No. 169,440

5 Claims. (Cl. 285—56)

This invention is predicated upon improvements in metallic tubular structures, and it is exemplified herein by tubular connections employed in fluid heat exchange apparatus.

5 When, in such apparatus, a fluid at one temperature passes through tubes to a metallic vessel at a higher temperature, experience has shown that the consequent differential metal expansions soon cause defects in the connections between the tubes 10 and the metal of the vessel. This is especially true of economizer tubes connected to the drums of steam boilers operating at high fluid pressures.

It is an object of the invention to overcome this disadvantage.

15 A further object is to provide a Stirling boiler with an integral economizer the tubes of which are joined to a feed-water drum in accordance with the teachings of this invention.

Other objects will appear from consideration of the following description of the Stirling water 20 tube steam boiler shown in the accompanying drawing, in which:

Figs. 1-5 inclusive are detail sections indicating different steps of a method which may be employed in practicing the invention.

25 Fig. 6 is a vertical section through a boiler drum having tubes connected thereto.

Fig. 7 is a section showing a tubular drum connection.

Fig. 8 is a view in the nature of a vertical section, showing a Stirling boiler having an integral economizer.

Figure 9 is a sectional view.

The drawing discloses a Stirling boiler including the mud drum 10 and the upper steam and water 35 drums 12, 14 and 16, the first of which is provided with a steam off-take 17. The latter drums are connected to the mud drum by separate banks of steam generating tubes 18, 20 and 22, exposed in separate gas passes to furnace gases from the 40 combustion chamber 24.

Feed water is supplied from any suitable source to the economizer drum 26 which is connected to the rear drum 16 by the economizer tubes 28 located in the last gas pass of the boiler. Although 45 the temperature of the feed water is raised during its movement through these tubes it may be at a temperature much less than the temperature of the drum 16 when it enters the latter. The tubes 28 therefore tend to contract relative to the metal 50 of that drum, causing a loosening of the tubes when they are directly expanded into the drum. Furthermore, this undesirable condition is aggravated by the continued supply of low temperature fresh feed water to the drum 26 and the

continued circulation through the drum 16 of water which has been heated to a higher temperature by the tubes 22 in the hottest gas pass. Such circulation takes place through the drum 10 which directly connects the banks of tubes 18 5 and 22.

When it is considered that many boilers of the type shown operate at fluid pressures in excess of 1000 lb. per sq. inch it will be readily appreciated that any loosening of the tubes 28 in their seats in the drum 16 is apt to be a matter of no small moment. As a matter of fact, experience has shown that such results are grave disadvantages in boilers operating at much lower pressures. This is particularly true when the boilers are operated 15 at 300 to 500% ratings. The water level in the drum 16 is apt to be below the upper ends of some of the tubes 28. The connections of these tubes with the drum are then apt to become loosened so that steam leaks develop. It finally becomes necessary to take the boiler off the line for repairs, and if the tubes are merely re-expanded into the drum, the same cycle is repeated. To avoid this excessive "outage" the economizer tubes are connected to the drum 16 in the manner described 20 25 below.

The end of a tube 28 is first swaged to produce a portion of smaller diameter. This is indicated by the full lines in Fig. 2, comparison with the dotted lines 30 of this figure indicating the effect of the swaging operation. There is, of course, a lengthening of the tube, and circumferential external ribs 32 and 34 may also be formed during the swaging. The swaging of the tubes makes it possible to use wider ligaments between the tubes and allows a higher pressure to be carried for a given thickness of drum shell. In constructions other than the Stirling boiler shown it is sometimes preferable to refrain from swaging down the ends of the economizer tubes where they are connected to the steam and water drum.

40 As the next step in the illustrative procedure a sleeve 36 is telescoped upon the swaged end of the tube. When this sleeve is of the internal diameter shown it fits tightly upon the ribs 32 45 and 34 and is held in position thereby, spaced from the exterior surface of the tube. It is preferably formed of some self-supporting material, and, under different embodiments of the invention the material may be paper, or a metal having a low fusing temperature. Low fusing point alloys may be used in some instances, and in others, a cellular heat insulating material. Tin and lead are examples of metals which may be used.

50 In the illustrative method, a tubular metallic 55

ferrule 40, preferably of the same material as the tube, is tightly telescoped over the sleeve 36. This may be done in some cases before the sleeve is placed in the position shown in Fig. 3, but the 5 particular sequence of these acts depends upon the sequence of the remaining method steps, as well as upon the materials used.

The sleeve 36 and the ferrule 40 both terminate coincidentally with the tube to facilitate the completion of the circumferential weld 42 which forms a fluid tight connection between the tube and the ferrule but the invention also contemplates the extension of the tube beyond the ferrule in some cases. The tube is now ready to be held within a 10 tube seat in the drum 16 while an expander is operated within the tube to form a rigid and fluid tight drum connection. When the circumferential grooves 43 and 44 are formed as parts of the tube seat, the expanding operation will cause some 15 of the metal of the ferrule to occupy the grooves to lock the ferrule more securely to the drum. Fig. 7 shows the grooves to be entirely filled with such metal. The expanding operation may also result in such a belling of the end of the tubes as 20 indicated at 46 in Fig. 7. This further locks the ferrule to the drum and tends to prevent any end-wise movement of the ferrule.

In some embodiments of the invention the ferrule 40 may be separately expanded against the 30 tube seats, and the tubes thereafter co-axially placed within and spaced from the ferrules so that the circumferential welds may then be completed. In these cases the ferrules may be additionally welded directly to the drum metal, and 35 this welding as well as the expanding of the ferrules may be done in the shop where the drum is manufactured. This promotes economy of manufacture by reducing erection costs.

When the boiler is put into operation after a 40 heat convertible material such as paper is used between the ferrule and the tube, the paper or the compound formed on heating the paper acts to insulate the main body of the ferrule from the tube. When tin, lead, or some low fusing 45 point alloy is used as the sleeve, the latter melts when the boiler is placed in operation, leaving an annular space between the ferrule and the sleeve.

In some embodiments of the invention the ribs 32 and 34 may not be employed. The sleeve may 50 fit the tube tightly throughout its length. Such an arrangement of elements is indicated in Fig. 9 of the drawing, wherein the ferrule 48 may be expanded into the drum in the shop and the tube thereafter inserted and welded to the inner end 55 of the ferrule in the field. With this construction there is an annular space between the tube and the ferrule.

The construction may be used to advantage 60 for connecting alloy steel superheater tubes to the outlet header of a superheater when the header is made of plain carbon steel. In such a case expanding the alloy steel tubes directly into the outlet header may result in leakage in a hydrostatic test of the superheater such as is usually 65 made during a shutdown period after the superheater has been in service. The coefficient of expansion and contraction of the alloy steel on changing the temperature is greater than in plain carbon steel and, on cooling down the superheater after it has been in operation, the alloy 70 steel tubes may leak where they are expanded into the carbon steel headers. By employing ferrules of plain carbon steel around the ends of the alloy steel superheater tubes arranged in the way shown and described and extending the 75

ferrules and tubes a sufficient distance into the header the difference in the expansion of the tubes and the ferrules will not cause the ends of the plain steel ferrules to become loose where they are expanded into the header as these ferrules will have the same coefficient of expansion as the header. This will overcome the tendency to leak on account of a difference in the coefficients of expansion. If desired, the ferrules may be welded to the header in which case it is 10 advantageous to have the same coefficient of expansion in the ferrules as in the header. By welding the ferrules to the header on the outside of the header the stresses due to the expansion of the tubes and the ferrules would be 15 distributed along the lengths of the ferrules thereby avoiding a concentration of stress due to the reinforcing action of the welding. The ferrules may be made of comparatively thin wall section because the tube ends would prevent 20 them from collapsing.

What is claimed is:

1. In fluid heat exchange apparatus, a thick walled pressure vessel in the nature of a drum or header, tubes of much less wall thickness communicating with the interior of the vessel and adapted in practice to conduct a liquid at lower temperature to the liquid supply in the vessel, metallic ferrules externally telescoped upon the ends of the tubes and spaced therefrom, a filler 25 interposed between each ferrule and its tube, and circumferential welds joining the inner ends of the tubes and the inner ends of the ferrules; each filler cooperating with a ferrule and a tube to maintain them in predetermined spaced relationship while the assembly is being expanded to form 30 a pressure tight joint between the ferrule and the metal of the drum.

2. In fluid heat exchange apparatus, a thick walled pressure vessel in the nature of a drum 40 or header, tubes of such less wall thickness communicating with the interior of the vessel and adapted in practice to conduct a liquid at lower temperature to the liquid supply in the vessel, metallic ferrules externally telescoped upon the 45 ends of the tubes and spaced therefrom, a filler interposed between each ferrule and its tube, the filler being formed of combustible material, and circumferential welds joining the inner ends of the tubes and the inner ends of the ferrules; each 50 filler cooperating with a ferrule and a tube to maintain them in predetermined spaced relationship while the assembly is being expanded to form a pressure tight joint between the ferrule and the pressure vessel.

3. In tubular connections between a steam and water drum and tubes through which water is adapted to enter the drum at a temperature lower than that of the body of fluid within the drum, the drum being formed with openings providing 60 tube seats, the tubes having reduced ends extending a substantial distance into the interior of the drum, sleeves or ferrules externally telescoping the tubes and circumferentially insulated therefrom, the ferrules extending similar distances into the interior of the drum, and circumferential welds formed at the inner ends of the tubes and ferrules while the latter are maintained in circumferentially spaced relationship 65 to the tubes, the ferrules and the tubes being 70 simultaneously expanded into the tube seats.

4. In fluid heat exchange apparatus, a thick walled pressure vessel in the nature of a drum or header, tubes of much less wall thickness communicating with the interior of the vessel and 75

adapted in practice to conduct a liquid at lower temperature to the liquid supply in the vessel, metallic ferrules externally telescoped upon the ends of the tubes and spaced therefrom, a filler 5 of a low fusing point metal interposed between each ferrule and its tube, and circumferential welds joining the inner ends of the tubes and the inner ends of the ferrules; each filler cooperating with a ferrule and a tube to maintain them in 10 predetermined spaced relationship while the assembly is being expanded to form a pressure tight joint between the ferrule and the pressure vessel.

5. In fluid heat exchange apparatus, a thick walled pressure vessel in the nature of a drum or 15 header, tubes of much less wall thickness communicating with the interior of the vessel and

adapted in practice to conduct a liquid at lower temperature to the liquid supply in the vessel, the pressure vessel ends of the tubes having pre-formed circumferential ribs, metallic ferrules externally telescoped upon the ribbed ends of the 5 tubes and spaces therefrom, a filler interposed between each ferrule and its tube, and circumferential welds joining the inner ends of the tubes and the inner ends of the ferrules; each filler cooperating with a ferrule and a tube to 10 maintain them in predetermined spaced relationship while the assembly is being expanded to form a pressure tight joint between the ferrule and the pressure vessel.
